Carburetor Corporation, St. Louis, Mo., a cor-
poration of Delaware

Application July 6, 1933, Serial No. 679,201

40 Claims. (Cl. 123—179)

This invention relates to carburetors and particularly to automatic control devices for controlling the fuel mixture under low temperature conditions. In previous devices of this character the use of a bi-metallic coil thermostat has been suggested but difficulties have been encountered in getting the thermostat to heat up quickly enough after the motor starts so as to open the choke valve as soon as the engine is in a warm enough condition to use a leaner mixture. Difficulty has also been encountered in obtaining a suitable means to open the throttle valve or otherwise to supply sufficient mixture to the engine to keep it running when the oil is cold and viscous. With the throttle in its normal closed position only sufficient air is admitted to the engine to produce power enough to turn it over at idling speed under normal temperature operating conditions so that if the throttle is left in this position when the oil is cold and viscous, the engine simply does not have power enough to run and it stops. Inasmuch as the throttle is normally held in closed position by a fairly stiff spring and since it is desired to reduce the bi-metallic coil thermostat to small proportions on account of expense, difficulty has been had in obtaining sufficient power to automatically open the throttle when the engine cools off between periods of operation. Another difficulty that has been had with previous installation is that the thermostat has generally been mounted on the exhaust manifold or the hot spot of the intake manifold, an arrangement which requires the coupling of the thermostat by comparatively long linkage to the choke valve of the carburetor, and since the carburetors are not usually manufactured in the same factories where the engine is built, the assembly of these parts is not done by carburetor men but by general automobile mechanics and improper adjustment frequently results.

The object of this invention is to produce a generally new and improved automatic device for controlling the admission of fuel to the engine under low temperature conditions and to eliminate or alleviate the above described difficulties. The invention will be better understood upon reference to the accompanying drawings, referring to which:

Figure 1 is a side elevation of a carburetor constructed according to my invention, parts being broken away and others shown in section.

Figure 2 is a sectional elevation of a carburetor constructed according to my invention, the view being taken from the side opposite to that shown

in Figure 1, and parts being broken away and others shown in section.

Figure 3 is a detail sectional view taken along the line 3—3 of Figure 2 looking in the direction of the arrows. 5

Figure 4 is a detail sectional view taken along the line 4—4 of Figure 1, looking in the direction of the arrows.

Figure 5 is a plan view of the device.

Figure 6 is a detail view taken along the line 6—6 of Figure 3, looking in the direction of the arrows.

The reference numeral 1 indicates the main body member of a carburetor mounted by means of a flange 2 on the intake manifold 3 of an internal combustion engine. The exhaust manifold is shown at 4. The carburetor comprises the usual throttle valve 5 controlled by a manually operated lever 6, a connection 7 to foot pedal or dash being provided. A float chamber 8 is formed integral with the main casting of the carburetor and fuel is maintained at substantially the level A—A by float mechanism diagrammatically indicated at 9. Fuel is supplied from the float chamber to a main nozzle 10 by means of the main jet 11 and a metering rod 12 is provided for controlling the main jet in accordance with the throttle position. The main nozzle 10 discharges at the throat of the venturi 13, which, in the present instance discharges into other and larger venturis to form a multi-stage mixing arrangement; this construction is already well known in the art, and no further description is necessary. A diaphragm 14 is subjected to the suction in the intake manifold of the engine by means of the conduit 15, is mounted on the body of the carburetor by means of the bracket 16 and connected to rocker arm 17 by means of the rod 18. A spring 19 is provided for moving the diaphragm to the right with respect to Figure 1 and this spring has sufficient strength to open the throttle valve by the means hereafter to be described, but the spring is still weak enough to be overcome by a suction in the intake manifold amounting to 6 or 7 pounds per square inch so as to permit the throttle to move to fully closed position. 30 35 40 45

The rocker arm 17 is fixedly mounted on the rock shaft 20 which is also provided with the lever 21 fixed thereto. The lever 21 is provided with a transversely bent portion 22 at its end 50 to insure contact with the lever 23 which is mounted on the throttle shaft 24. Obviously when there is no suction in the intake manifold, spring 19 pushes diaphragm 14 to the right with respect to Figure 1 and rotates shaft 20 in a 55

clockwise direction thereby causing the transverse portion 22 to contact with and move the lever 23 to slightly open the throttle as soon as the engine stops and to hold it there until the engine is cranked again and begins to run under its own power. A second lever 25 is mounted on the throttle shaft to rotate therewith and connected by means of link 26 with rocker arm 27 carried by rock shaft 28. The link 26 is provided with an inwardly projecting pin 29 for a purpose hereafter to be described.

The choke valve 30 is eccentrically mounted on shaft 31 which extends thru the wall of the air horn 32 and is provided at one end with an arm 33 having a slot 34 therein. A link 35 has a pin 36 loosely mounted in slot 34 and serves for connecting the choke valve to a rocker arm 37 which is pivotally mounted on the pillow block 38 by means of the pin 39. The rocker arm 37 is provided with a lug 40 adapted to contact the corresponding lug 41 carried by the rocker arm 27. When the choke valve is in the closed position as indicated in Figure 1, the normal position of the lug 40 is such as to prevent anti-clockwise movement of the rocker arm 27 by reason of contact between lugs 40 and 41. This position of rocker arm 27 corresponds to a slightly open position of the throttle valve and insures the supply of sufficient air to the engine to keep it in operation at low temperatures. Whenever the choke is moved to open position, the rocker arm 37 is moved in a clockwise direction with respect to Figure 1 and lug 40 is moved out of the path of lug 41 permitting the throttle valve to be returned to its normal idling position. Due to the provision of the slot 34, there is no interference between the lugs 40 and 41 during a closing movement of the choke valve even if, for some reason, the throttle valve should be in fully closed position. In case of failure of the diaphragm 14 to move the throttle valve to partially open position when the engine stops, the choke valve would be moved to fully closed position upon the subsequent cooling of the engine, and the throttle valve would remain in closed position until it should be operated manually. As soon as the throttle valve is operated manually to a sufficiently open position, the rocker arm 37 would drop down by gravity to the position indicated in Figure 1, and the re-closing of the throttle would be prevented until the choke valve had been opened sufficiently to move the lug 40 out of the path of lug 41.

The other end of the choke valve shaft 31 extends into a housing 42 which is thoroughly lined with cork or other heat insulating material as indicated at 43. The casing is formed in two parts as indicated in Figure 3, the outer portions being cup-shaped and removable, and a radial lever arm 44 is rigidly secured to the end of the choke valve shaft 31 within the housing 42. The end of the lever 44 is connected to a disk-shaped piston 45 by means of the curved connecting rod 46 as indicated in Figure 2. This piston 45 operates in a chamber 47 which is formed within the housing 42 in the shape of a portion of an annulus so that the piston 45 may simultaneously slide within the cylinder 47 and rotate about the center of the shaft 31. The cylinder 47 is provided with grooves or by-passes 48 formed on its opposite flat sides. The by-passes do not extend the full length of the cylinder and when the piston 45 is in the position shown in Figure 2, the by-passes are closed by the piston,

also when the piston 45 is moved as far as it will go in a clockwise direction with respect to Figure 2, the by-passes are again closed. The by-passes 48 are formed with an irregular contour so as to provide an uneven suction action on the piston 45. In order to provide for variations in the circularity of the cylinder 47, the piston 45 is pivoted to the connecting rod 46 as indicated at 49. In order to obtain heat for warming up the thermostat when the engine starts, a hot air stove 50 is provided on the exhaust manifold 4 and hot air is drawn up from the stove directly thru the conduit 51 to the interior of the housing 42. The moving force which draws the hot air thru the housing 42 is the suction of the intake manifold which is conveyed by means of a conduit 53 to the cylinder 47 in such a manner that the suction existing in the intake manifold is transmitted to the piston 45 and whenever the piston 45 has been moved in a clockwise direction with respect to Figure 2 far enough to uncover the by-pass 48, a strong draught of hot air is drawn from the conduit 51 thru the housing 42 and the by-pass 48, thus warming up the inside of the housing and the thermostat 54. The conduit 53 is provided with a valve screw 55 by which the suction may be regulated. The thermostat 54 is fixedly mounted on the removable portion of the housing 42 by means of a pin 55. The outer portion of the housing is held in place by means of a flexible bracket 56 of well known construction. This bracket is pivoted at 57 so that it may be swung aside to permit complete removal of the thermostat and the outer portion of the housing. The thermostat may be rotatably adjusted by turning the housing to the right or left and will be held in adjusted position by friction created by the pressure of the flexible bracket 56 against the outer portion of the housing.

The outer end of the thermostatic coil is provided with a hook which engages the pin 58 which projects from the lever 44. The thermostat is of the bi-metallic coil type and the metals are so arranged as to rotate the lever 44 and the choke valve in an anti-clockwise direction with respect to Figure 2 when the temperature is low; in other words the choke valve will be closed when the engine is cold.

It will be noted that the hook on the end of the thermostatic coil which engages the pin 58 operates the choke valve in one direction only. The reason for this form of connection is to permit the thermostat to freely move without obstruction by any other element when the temperature is high, it being a well known characteristic of thermostats that they must not be subjected to strain when the temperature is above a predetermined degree. It will also be understood that the thermostat is, in effect, connected to the choke valve although the connection is such as to act in one direction only.

I have found it highly desirable to provide a fluttering action for the choke valve during the cranking of the engine. In order to do so I provide a magnet 59 which may have the regular horse-shoe shape or be slightly curved as indicated in Figure 2. This magnet is held in place by means of the brass screw 60 and the lever 44 has an upturned portion 61 which serves as an armature for the magnet. The member 61 is, of course, constructed of iron or other magnetic material and contacts with the poles of the magnet when the choke valve is moved to fully closed position. It should be clearly under-

stood that the magnet 59 is not of great strength, and its effect on the closing movement of the choke valve is completely negligible until the armature 61 is brought in substantial contact 5 with the magnet. The thermostat 54 is the only device supplying any substantial amount of power to move the choke valve toward closed position. It should also be noted that the magnet 59 is not even strong enough to offer any 10 substantial resistance to the opening of the choke valve. The purpose of the magnet is to obtain a fluttering action of the choke valve during the cranking period and the amount of force required to set up this fluttering action is almost 15 negligible.

The reason a fluttering action is desirable is substantially as follows:

When the engine is being cranked with the choke valve closed, there is substantial suction 20 in the mixing chamber of the carburetor resulting in the discharge of large quantities of fuel from the main nozzle 10, but the rate of air flowing thru the mixing chamber 65 of the carburetor is practically nil, the only air being admitted 25 with the choke valve in closed position being the leakage past said valve. Obviously it takes a current of air to carry vaporized fuel to the engine. Otherwise it would be necessary to wait until the intake manifold practically filled 30 up with liquid fuel before the cylinders received any. In previous constructions this small amount of air for conveying the original charges has been supplied by means of a bleeder hole, or 35 small check valve mounted within the choke valve or in some equivalent location. Such devices supply a small constant current moving at low speed and most of the fuel vapor carried by such current was either condensed on the walls of the manifold or otherwise precipitated the 40 moment it reached the cylinders. One of the objects of this invention is to secure the movement of the air current from the carburetor to the cylinders in a succession of comparatively rapid impulses instead of in a steady flow or 45 stream, the impulsive movement apparently having a better vaporizing effect on the gasoline and being more efficient to retain the gasoline in vaporized position. One reason for this improved result is, of course, that the current moves 50 in impulses and the individual impulses move at a much higher velocity when the air is admitted intermittently than would be obtained if the air was admitted constantly thru a small orifice.

In operation when the motor is not running there is no suction in the intake manifold and the spring 19 moves diaphragm 14 to the right 55 with respect to Figure 1, causing the partial opening of the throttle valve so as to admit ample fuel mixture to the engine during the cranking period and during the first few revolutions when it runs under its own power. The throttle valve being moved to partly open position, raises the link 26 and rotates rocker arm 27 in a clockwise direction with respect to Figure 1, lifting the lug 41 up beyond the end of the lug 40. The choke valve is moved to closed position by the thermostat and the piston 45 is moved by the same means to the position shown in Figure 2. 60 As soon as the engine starts to run under its own power, suction transmitted thru the conduit 15 will move the diaphragm 14 to the left with respect to Figure 1, overcoming the pressure of spring 19 and permitting the throttle valve to move toward closed position until the 65

lug 41 contacts with the lug 40, thereby preventing the complete closing of the throttle valve and leaving it in the fast idle position. During the cranking period the choke valve is intermittently opened by the suction and closed again 5 by the thermostat at a fairly rapid rate, the fluttering action being caused by the effect of the magnet 59. It will be understood that the magnet has somewhat the effect of a snap action device which prevents the choke valve remaining fixed in a position which would leave the armature 61 in close proximity to the poles of the magnet but not contacting therewith. For instance if the armature 61 is within a $\frac{1}{16}$ 10 of an inch of the poles of the magnet, the combined strength of the thermostat and the magnet would generally be sufficient to move it quickly to fully closed position, the action of the suction being elastic and the movement of the piston of the engine being slow during the cranking period, so that an appreciable length of time is required to build up sufficient suction to overcome the combined action of the thermostat and the effects of the magnet on the armature 15. When the suction is built up to such a point 20 that it is strong enough to break the armature away from the poles of the magnet it is also strong enough to carry the valve a substantial distance beyond that necessary to admit the air at the rate at which it is being drawn in by 25 the cylinders. The suction in the carburetor and intake manifold is accordingly immediately reduced to practically nothing and the choke valve swings back toward closed position under 30 the influence of the thermostat, acquiring sufficient momentum in doing so to move the armature 61 into contact with the poles of the magnet, and then the operation is repeated.

As soon as the engine begins to run under its own power, a substantial amount of suction is 35 developed in the intake manifold and this suction is transmitted thru the conduit 53 to cylinder 47 and piston 45. It will be understood, of course, that there is some suction in the intake manifold even during the cranking period, and 40 this contributes to a certain extent to the opening of the choke valve during the cranking period, but the effect is more or less minimized by the fact that the piston 45 does not fit tightly 45 and there is some leakage around it in the cylinder 47. When the engine is running under its own power, however, the suction is built up in the intake manifold to such a value that the effect on piston 45 is very definite, being strong 50 enough to overcome the action of the thermostat and open the choke valve to an extent depending on the temperature, the speed at which the engine may be running and on the position of the throttle valve 5. This movement of the piston 45 in a direction to open the choke valve also 55 opens the passageway thru by-pass 48 which permits hot air to be drawn up rapidly from the air stove 50. It will be understood, of course, that the air is not warm during the first few seconds of the running of the engine, but since 60 the stove is mounted on the exhaust pipe it is only a short time until it becomes heated up. The high suction in the intake manifold draws a strong draught from the stove 50 which, of course, is open to the atmosphere and the thermostat in the insulated housing 42 is quickly 65 warmed up so that the choke valve is soon moved to full open position.

In order to properly control the movements of the choke valve in response to the action of 70

the piston 45, the capacity of the conduit 53 may be controlled in any suitable manner. This control may be accomplished by merely selecting a proper size for the tube 53 or by the insertion 5 of a restricted orifice or an adjusting valve as shown at 75 or any other suitable means. A similar adjustment could also be made for the conduit 51.

As the choke valve approaches full open position, the piston 45 moves to a position to restrict 10 the flow of hot gas thru the cylinder 47, and prevents further heating up of the thermostat. It will be understood, however, that during continued operation of the engine, the leakage past 15 the piston 45 is sufficient to keep the thermostat 54 hot to maintain the choke valve in fully open position. It is not necessary, however, to exceed temperatures of approximately 200 degrees Fahrenheit in the chamber 54 so that comparatively inexpensive thermostatic metal may be used.

Once the thermostat has been moved to fully open position the insulation 43 prevents the rapid cooling of the thermostat and avoids the 25 supply of an over-rich mixture to a motor which has been recently operating and has not yet cooled down to a point where such rich mixture is required.

In case the engine does not start during the 30 initial cranking it may become over-loaded and in such case it is desirable to provide manual means for opening the choke valve when clearing out the engine. Such means are provided in the pin 29 which contacts with the lower part of 35 the lever 37 when the throttle valve is moved to fully open position so that the operator can, by simply holding the throttle open, push the link 26 upwardly rotating the arm 37 in clockwise direction with respect to Figure 1 and opening 40 the choke valve so that with a few seconds further cranking the cylinders can be relieved of the excess gasoline.

The irregular contour of the by-passes 48 is 45 provided in order that the mixture ratio of air and gasoline may be definitely controlled for any particular engine by changing the contour. As the piston 45 moves in a clockwise direction with reference to Figure 2, the pull of the suction upon the piston is varied according to the particular contour of the by-passes thereby causing 50 the choke valve 30 to be opened a predetermined distance for any particular suction which may be set up in the intake manifold. This action is provided in order that there may be greater 55 economy and more efficient operation.

The invention is not limited in details to the structure shown but may be modified in various respects as will occur to those skilled in the art and the exclusive use of all such modifications that come within the scope of the appended 60 claims is contemplated.

A part of the subject matter shown but not claimed herein is shown and claimed in applicant's divisional application, Serial No. 117,822, filed December 28, 1936, for improvements in Carburetors, and in applicant's application, Serial No. 134,070, filed March 31, 1937, for improvements in Carburetors, which is a continuation, in part, of the present application.

70 I claim:

1. In an internal combustion engine having an intake manifold and an exhaust manifold, a carburetor mounted on said intake manifold, said carburetor having a choke valve, a housing 75 mounted on said carburetor, a conduit having an

inlet end open to the atmosphere at a point adjacent said exhaust manifold, said conduit having an outlet discharging into said housing, a second conduit having an inlet discharging within said housing and an outlet opening into said intake manifold, a heat responsive device mounted within said housing, means for transmitting a movement of said heat responsive device to said choke valve, and a suction operated device for affecting the richness of the mixture delivered 10 by the carburetor in accordance with suction conditions.

2. In an internal combustion engine having an intake manifold and an exhaust manifold, 15 a carburetor connected to said intake manifold, said carburetor having a choke valve, an air heating device on said exhaust manifold, a housing on said carburetor adjacent said choke valve, a heat responsive device for operating said choke valve, means for conveying air from said 20 air heating device to said housing, said means including a conduit having an outlet end within said housing, a suction responsive device in said housing for operating the choke valve, a suction conduit for said suction responsive device, 25 and said suction conduit having an inlet from said housing to cause the flow of heated air therethrough.

3. In an internal combustion engine having an intake manifold and an exhaust manifold, a 30 carburetor mounted on said intake manifold, said carburetor having a choke valve, a heat responsive device and a suction responsive device connected to said choke valve, an insulated 35 housing enclosing said heat and suction operated devices, a suction connection between said housing and said inlet manifold for operating said suction operated device, an air heating device mounted on said exhaust manifold, and a conduit for conveying heated air from said air 40 heating device to said housing.

4. In an internal combustion engine having an intake manifold and an exhaust manifold, a carburetor mounted on said intake manifold, said carburetor having a choke valve, a heat responsive device and a suction responsive device connected with said choke valve, a housing enclosing said heat and suction responsive devices, a suction connection between said housing and said inlet manifold for operating said suction responsive device, an air heating device mounted on said exhaust manifold, and a conduit for conveying heated air from said air heating device to said housing, said suction responsive device being constructed and arranged to by-pass a certain amount of air when the choke valve is in partly open position and to substantially close the by-pass when the choke valve is in fully open position.

5. In an internal combustion engine having an 60 intake manifold and an exhaust manifold, a carburetor mounted on said intake manifold, said carburetor having a choke valve, a heat responsive device and a suction responsive device connected with said choke valve, a housing 65 enclosing said heat and suction responsive devices, a suction connection between said housing and said intake manifold for operating said suction responsive device, and an air heating device mounted on said exhaust manifold, a conduit for conveying heated air from said air heating device to said housing, said suction responsive device being constructed and arranged to by-pass a certain amount of air when the choke valve 70 is in partly open position and to substantially close the by-pass when the choke valve is in fully open position.

close the by-pass when the choke valve is in fully open position, said suction responsive device being also constructed and arranged to substantially prevent the by-passing of air when 5 the choke valve is in fully closed position.

6. In a carburetor, a choke valve, a shaft for said choke valve, an operating lever mounted on said shaft, a connecting rod having a circular axis connected to said lever and substantially 10 concentric with said shaft, a piston on one end of said connecting rod, and suction means for operating said piston.

7. In a carburetor, a choke valve, a choke valve shaft, an expansible chamber in the form of a 15 portion of an annulus surrounding said shaft, a connecting rod connected to said lever and made in the form of a portion of a circle concentric with said shaft, and a piston for said connecting rod slidably mounted within said expansible 20 chamber.

8. In a carburetor, means forming a mixing conduit, a choke valve mounted at the inlet of said mixing conduit, a choke valve shaft mounted transversely with respect to said mixing conduit and attached to said choke valve, said shaft being eccentric with respect to said choke valve, whereby the choke valve may be moved toward 25 open position by suction, an operating lever mounted on said shaft, a cylinder having a curved axis concentric with the axis of said shaft, a piston in said cylinder, a rod connecting said piston with said lever, and means for applying suction to one end of said cylinder.

9. In a carburetor, means forming a mixing 35 conduit, a choke valve mounted at the inlet of said mixing conduit, a shaft transversely mounted in said mixing conduit and attached to said choke valve, said shaft being eccentric with respect to said choke valve, whereby the choke 40 valve may be moved toward open position by suction, an operating lever for said shaft, a cylinder having a curved axis concentric with the axis of said shaft, a piston in said cylinder, a rod connecting said piston and said lever, and 45 means for applying suction to one end of said cylinder, said means comprising a conduit connected to the intake manifold of the engine.

10. In a carburetor, means forming a mixing 50 conduit, a choke valve mounted at the inlet of said mixing conduit, a transverse shaft mounted in said mixing conduit and attached to said choke valve, said shaft being eccentric with respect to said choke valve, whereby the choke valve may be moved toward open position by suction, an 55 operating lever for said shaft, a cylinder having a curved axis concentric with the axis of said shaft, a piston in said cylinder, a rod connecting said piston with said lever, means for applying suction to one end of said cylinder, and a heat 60 responsive device for moving said choke valve toward closed position.

11. In a carburetor means forming a mixing 65 conduit, a choke valve mounted at the inlet of said mixing conduit, a transverse shaft mounted in said mixing conduit and attached to said choke valve, said shaft being eccentric with respect to said choke valve, whereby the choke valve may be moved toward open position by suction, an operating lever for said shaft, a 70 cylinder having a curved axis concentric with the axis of said shaft, a piston in said cylinder, a rod connecting said piston and said lever, means for applying suction to one end of said cylinder, a heat responsive device for moving said 75 choke valve toward closed position, and means

for setting up a fluttering action of said choke valve during the cranking of the motor.

12. In a carburetor, means forming a mixing conduit, a choke valve mounted at the inlet of said mixing conduit, a transverse shaft mounted 5 in said mixing conduit, and attached to said choke valve, said shaft being eccentric with respect to said choke valve, whereby the choke valve may be moved toward open position by suction, an operating lever mounted on said shaft, 10 a cylinder having a curved axis concentric with the axis of said shaft, a piston in said cylinder, a rod connecting said piston and said lever, means for applying suction to one end of said cylinder, a heat responsive device for moving 15 said choke valve towards closed position, and means for setting up a fluttering action of said choke valve during each individual suction stroke of the motor during the cranking period.

13. In a carburetor, means forming a mixing 20 conduit having a throttle controlled outlet and a choke controlled inlet, a choke shaft, heat and suction responsive devices operatively associated with said shaft, a housing for said heat responsive device, and insulating means for preventing 25 the rapid transfer of heat away from said heat responsive device.

14. In a carburetor, means forming a mixing 30 conduit having a throttle controlled outlet and a choke controlled inlet, a choke shaft, heat and suction responsive devices operatively associated with said shaft, means for heating said heat responsive device, a housing for said heat responsive device, and insulating means for preventing 35 the rapid transfer of heat from said heat responsive device to the outer atmosphere.

15. In a carburetor, an air horn having a choke 40 valve therein, a shaft for said choke valve mounted within said air horn, a housing mounted on said air horn at one end of said choke valve shaft, a heat responsive device within said housing, means for heating said heat responsive device, and insulating means to prevent the rapid transfer of heat away from said heat responsive 45 device.

16. In a carburetor, an air horn having a choke valve mounted therein, a shaft for said choke valve mounted in said air horn, a heat responsive element mounted on said air horn at one end of said shaft, a housing for said element, 50 means for admitting heated air to said housing, a suction connection from said housing to the intake manifold of the engine, a part of said connection being formed to receive a suction responsive element, and a suction responsive element 55 loosely mounted in said part of the connection.

17. In a carburetor, an air horn having a choke valve mounted therein, a shaft for said choke valve mounted in said air horn, a heat responsive 60 element mounted on said air horn at one end of said shaft, said heat responsive element being constructed and arranged to close said choke valve when the temperature is low, a housing for said element, means for admitting heated air to 65 said housing, a suction passageway leading from said housing to a suction producing device, whereby heated air is caused to flow through said housing to said suction producing means, and a suction responsive element connected to 70 said choke valve, said suction responsive element being exposed to the suction in said suction passageway and adapted to be operated thereby.

18. In a carburetor, an air horn having a choke valve mounted therein, a shaft for said choke 75

- valve mounted in said air horn, a heat responsive element mounted on said air horn at one end of said shaft, a housing for said element, means for admitting heated air to said housing, 5 a suction connection from said housing to the intake manifold of the engine, a suction responsive element mounted in a part of said connection and connected to the choke valve, and means for restricting said suction connection when the 10 choke valve is in fully closed position.
19. In a carburetor, a choke valve, a heat responsive element for controlling said choke valve, means for applying heat to said heat responsive element, and means for controlling the application 15 of said heat in accordance with the position of said choke valve, said last named means including a suction responsive element which is connected with the choke valve.
20. In an internal combustion engine, a carburetor having a choke valve, a heat responsive device for controlling said choke valve, an air heating device, a housing for said heat responsive device, means for causing the flow of heated air from said air heating device thru said housing to heat said heat responsive element, and means for controlling the rate of flow of said 25 heated air in accordance with the position of said choke valve, said last named means including a suction responsive element which is connected with the choke valve.
21. In an internal combustion engine, a carburetor, an intake manifold and an exhaust manifold, a choke valve for said carburetor, an air heating device mounted on said exhaust manifold, a housing, a heat responsive element within said housing, said heat responsive element being constructed and arranged to close said choke valve when the temperature is low, an air passage 30 from said air heating device to said housing, a suction operated device connected with said choke valve and receiving air from said housing, a suction connection from the intake manifold to said suction operated device, said suction operated device being constructed and arranged to by-pass varying amounts of air in accordance 35 with the position of said choke valve.
22. In a carburetor, a choke valve, a suction responsive device for operating said choke valve, said suction responsive device comprising a piston 40 and a cylinder, means including a restricted conduit for applying suction to said cylinder, said cylinder being slightly larger than said piston and varied in size at different points of its length, whereby the responsiveness of said piston to suction will vary in accordance with the position of said piston in said cylinder.
23. In a carburetor, a choke valve, a suction responsive device for operating said choke valve, said suction responsive device comprising a piston 45 and a cylinder, means including a restricted conduit for applying suction to said cylinder, said cylinder being slightly larger than said piston and varied in size at different points of its length whereby the responsiveness of said piston to suction will vary in accordance with the position of said piston in said cylinder, and a heat responsive device for controlling said choke valve.
24. In a carburetor, a choke valve, a suction 50 responsive device for controlling said choke valve, said suction responsive device comprising a piston and cylinder, said piston having a close fit at each end of said cylinder and a loose fit in the middle of said cylinder whereby the responsiveness of said device to suction will be less in an intermediate position than in either of its extreme positions.
25. In a carburetor, an air horn, a choke valve mounted in said air horn, a housing mounted on said air horn, a heat responsive element within said housing for controlling said choke valve, a suction responsive device within said housing for exercising a further controlling effect on said choke valve, an air heating device for delivering heated air to said housing, a suction connection for applying a suction to said suction responsive device, said suction responsive device comprising a cylinder open at one end of said housing and a piston within said cylinder, said cylinder being provided with a by-pass for permitting the rapid withdrawal of heated air from said housing when said piston is in a predetermined position.
26. In an internal combustion engine, an intake conduit, a carburetor communicating therewith, a throttle valve in said carburetor, a choke valve in said carburetor and responsive to suction therein, a suction responsive device for influencing said choke valve, said device communicating with said intake conduit, and a heat responsive device for urging said choke valve towards its closed position when the engine is cold, said suction responsive device also communicating with a stove adjacent the engine and functioning to cause fluid from said stove to flow past said heat responsive device.
27. In an internal combustion engine, an intake conduit, a carburetor communicating therewith, a choke valve in said carburetor, a heat responsive device for influencing said choke valve, means for exposing said device to engine heat, and means responsive to suction in said conduit for controlling said first mentioned means.
28. In an internal combustion engine having an intake passage and an exhaust passage, a device for supplying fuel mixture to said intake passage including a heat responsive device for controlling the richness of the mixture supply inversely in accordance with the temperature, a suction responsive device for controlling the richness of the mixture inversely in accordance with suction, a housing for said heat and suction responsive devices, means for supplying heat to said heat responsive device, and a suction connection for conveying suction from said intake passage to said suction operated device.
29. In an internal combustion engine having an intake conduit provided with a choke valve and an exhaust conduit, a device for supplying fuel mixture to said intake conduit including a housing, a heat responsive device and a suction responsive device in said housing, said heat and suction responsive devices having connections for operating said choke valve, a conduit for conveying air heated by said exhaust conduit to said housing for heating said heat responsive device, said suction responsive device comprising a piston having one end exposed to the pressure within said housing, and a suction connection for applying suction from said intake conduit to the other end of said piston.
30. A device as described in claim 29, and in which said intake conduit is provided with a throttle, and said suction connection is connected to said intake passage at a point posterior to the throttle.
31. In a carburetor having a choke valve and a throttle, a shaft for the choke valve, a thermostatic spring operatively connected to the shaft to rotate the same, a casing enclosing the thermostatic spring, means for conveying heat to said

casing, a cylinder having one end communicating with said casing and its other end connected to a source of variable pressure, a piston in said cylinder, and means connecting the piston with the choke valve whereby movement of the piston will cause a movement of said choke valve.

32. In a carburetor, a throttle, an unbalanced choke valve mounted on a shaft, a bimetallic spring connected to said shaft to rotate the same, a casing enclosing said spring, a conduit for conveying heated gases to the casing, and a pressure-responsive member having one surface subject to the pressure in the casing and another surface subject to the suction posterior to the throttle, said pressure-responsive member being provided with means connecting it to the choke valve whereby movement of the pressure-responsive member varies the position of said choke valve.

33. In a carburetor, a throttle, a pressure-responsive choke valve mounted on a shaft, a thermostatic spring of spiral form connected to said shaft to rotate the same, a casing enclosing the thermostatic spring, a conduit for conveying heated air to the casing, a cylinder communicating with the casing, and a piston therein having one face subject to the pressure in the casing and its opposite face subjected to pressures posterior to the throttle, said piston being provided with means connecting it to the choke valve, whereby movement of the piston will vary the position of the said choke valve.

34. In a carburetor for an internal combustion engine, a throttle, a pressure-responsive choke valve mounted on a shaft, a thermostatic spring connected to said shaft to yieldingly urge the choke valve toward closed position at low temperatures, a casing fixed to the outer wall of the carburetor and enclosing the thermostatic spring, a conduit for conveying heated gases from a heated portion of the engine to the casing, a conduit leading from the casing to a point posterior to the throttle, and means for varying the position of the choke valve comprising a pressure-responsive member in said last mentioned conduit subject to the varying pressures therein and applied to the choke valve by an overrunning connection.

35. In a carburetor for an internal combustion engine, a throttle, a pressure-responsive choke valve mounted on a shaft, a spiral bimetallic spring connected with said shaft to yieldingly urge the choke valve toward closed position at low temperatures, a casing fixed to the outer wall of the carburetor and enclosing the thermostatic spring, a conduit for conveying heat from a heated portion of the engine to the casing, a second conduit leading from the casing to a source of suction, and means for varying the position of the choke valve comprising a piston in said second conduit connected to the choke valve by an overrunning connection.

36. In a carburetor for an internal combustion engine, an air inlet passage, an induction passage, a throttle valve controlling the induction passage, an unbalanced choke valve controlling the air inlet passage, temperature responsive means controlling the choke valve and adapted to move the choke valve in the closing direction at low temperatures, a casing carried by the walls of the air inlet passage and enclosing said temperature responsive means, means including a conduit to convey heated gases from a heated por-

tion of the engine to the interior of the casing, means including a conduit interconnecting the casing and the induction passage posterior to the throttle valve, and means including a pressure responsive member in said last mentioned conduit subject to varying pressures therein for varying the position of the choke valve. 5

37. In a carburetor for an internal combustion engine, an induction passage, an air inlet passage communicating with the induction passage, a 10 throttle valve controlling the induction passage, an unbalanced pressure responsive choke valve controlling the air inlet passage, a casing fixed to the outer walls of the air inlet passage, a choke shaft journalled in the walls of the air inlet passage and projecting into said casing, temperature responsive means in the casing and operably connected to the choke shaft to modify the position of the choke valve in accordance with the temperature of the engine, means including a conduit 15 to convey heated gases from the engine to the casing, means including a conduit interconnecting the casing and the induction passage beyond the throttle valve and a pressure responsive member in the conduit to vary the position of the choke 20 valve. 25

38. In combination with an internal combustion engine, a carburetor having a throttle and a pressure responsive choke valve, temperature responsive means for yieldingly urging the valve toward closed position and rendered inoperative at high temperatures, and means responsive to suction posterior to said throttle for moving the valve toward open position against the force of 30 said temperature responsive means, and means 35 whereby said choke valve will be moved to its full open position irrespective of said suction responsive means.

39. In combination with an internal combustion engine, a carburetor having a choke valve, 40 temperature responsive means yieldingly urging the valve toward closed position at low temperatures, additional means resisting opening movement of the valve, and suction operated means operative to render said additional means inoperative and to move the valve to at least partially 45 opened position against the force of the temperature responsive means, said choke valve being moved to fully open position when the normal operating temperature is reached or exceeded and 50 remaining in such fully open position as long as said normal operating temperature is maintained or exceeded regardless of suction.

40. In combination with an internal combustion engine, a carburetor having a throttle and 55 a pressure responsive choke valve, means operative below a predetermined temperature to yieldingly urge the valve toward closed position, additional means resisting opening movement of the valve, and means responsive to a predetermined suction posterior to the throttle for rendering said additional means inoperative and for moving the valve to at least partially opened position against the force of the temperature responsive means, said choke valve being moved to 60 fully open position when the normal operating temperature is reached or exceeded and remaining in such fully open position as long as said normal operating temperature is maintained or exceeded regardless of suction. 70
